THOMAS M. MCKEE, OF CONNERSVILLE, INDIANA.

EXTENSION-TABLE.

1,251,257.

Specification of Letters Patent. Patented Dec. 25, 1917.

Application filed January 6, 1915. Serial No. 862.

To all whom it may concern:

Be it known that I, THOMAS M. MCKEE, a citizen of the United States, residing at Connersville, in the county of Fayette and State of Indiana, have invented a new and useful Extension-Table, of which the following is a specification, reference being had to the accompanying drawings, and to the letters and figures of reference marked thereon.

The invention relates to tables of the type that is designed to be extended or contracted to different lengths, more especially when used in dining rooms; the invention having reference more particularly to supporting and guiding means for the movable end parts of the table, and means for controlling the adjustment of the end parts so that they shall always be in balance on opposite sides of the middle of the table structure.

An object of the invention is to provide improved guides and slides which shall be so constructed as to permit the table to be easily extended or contracted with the minimum amount of friction. Another object is to provide improved means for controlling the adjusting movements of the table, and without adding greatly to the cost of construction of extension tables. A still further object is to provide an improved extension table of such construction as to permit of the use of either a central pedestal or any suitable number of legs as may be desired, and which will be durable and economical in use.

With the above-mentioned and other objects in view, the invention consists in improved extension table construction embodying novel anti-frictional appliances and also novel equalizing appliances; the invention consisting further in the novel parts, and combinations and arrangements of parts, as hereinafter particularly described and further defined in the accompanying claims.

Referring to the drawings:—Figure 1 is an elevation of an extension table having a non-dividing pedestal and constructed substantially in accordance with the invention, the table top being indicated by broken lines in extended position; Fig. 2 is an end view of the improved guide bar; Fig. 3 is a fragmentary perspective view of the improved slide and equalizing device connected thereto; Fig. 4 is an end view of the improved guide bar and slides provided with the

equalizing device, the slides being shown in their relation to a fragment of the table top; Fig. 5 is an inverted plan of the table top extended and the invention applied thereto; Fig. 6 is a fragmentary top plan of the guide bar; Fig. 7 is a section of the guide bar in normal position on the line A A on Fig. 5; Fig. 8 is a section of the guide bar in normal position on the line B B on Fig. 65; Fig. 9 is a section in normal position on the line C C on Fig. 5, portions being broken away and the table being shown in contracted arrangement; Fig. 10 is a side elevation of the guide bar viewed from the opposite side of that seen in the preceding figure; and, Fig. 11 is a rear elevation of the improved slide partially broken away.

On the different figures of the drawings, similar reference characters indicate like elements or features of construction herein referred to.

A practical embodiment of the invention comprises a center piece 1 which in some cases is fixedly secured upon a pedestal or leg 2 and supports a suitable number of guide bars, there being preferably two bars 3 and 3' which are substantially alike and may be either identically constructed or varied slightly as to equipment thereof so as to form a pair of right and left guide bars. The bars preferably are provided with lag-bolts 4, 5, and 4', 5', respectively, that are provided with wing nuts 6, 6', whereby the bars are removably secured to the center piece. It will be obvious that the guide bars may be provided with any suitable number of supports that may be preferred.

The guide bars are most economically composed of wood, and each one is grooved in its opposite vertical sides throughout the length thereof so that two recessed bearing walls 7 and 8 are formed and also two horizontal track bearings 9 and 10 and oppositely arranged guide bearings 11 and 12. The top of each guide bar is rabbeted along the two longer edges thereof whereby a central longitudinal guide rib 13 is formed on the top of the bar. The upper portion of each bar has recesses 14 and 14' in opposite end portions and in opposite sides respectively of the bar to receive guide rollers behind the planes of the bearing walls 7 and 8 respectively. A suitable number of track rails are provided which preferably are composed of sheet metal and bent to the required formation. There are two track

rails for each guide bar and they comprise base portions 15 and 15' that are seated against the walls 7 and 8 respectively and secured thereto by means of screws 16, the 5 rails having track portions 17 and 17' on the outer edges of which are guards or retaining flanges 18, 18', that extend upward and stiffen the track portions. The upper edges of the base portions have horizontal 10 guide portions 19 and 19' thereon respectively that extend horizontally above the track portions and have downwardly extending guards 20 and 20' thereon respectively, the rails being designed to prevent 15 the wheels from being displaced laterally therefrom while guiding the wheels. Guide rollers 21 and 21' are arranged in the recesses of each guide bar 14 and 14' respectively on horizontal axles 22 that are 20 secured in the guide bars. The periphery of each roller is slightly above the top of the guide bar adjacent to the guide rib 13 to afford bearings for the slides. Two slides are assembled on each guide bar and are 25 composed of suitable metal, each being L-shaped in cross-section. All the slides are substantially alike, or may be slightly varied in arrangement as illustrated so as to form right and left pairs. The two slides on the 30 guide bar 3 comprise base portions 23 and 24, those on the bar 3' comprising base portions 25 and 26 respectively. The base portions 23 and 24 are horizontal and have downwardly extending side bars 27 and 28 35 on opposite sides respectively of the guide bar 3. The base portions 25 and 26 have side bars 29 and 30 on opposite sides respectively of the guide bar 3'. Two tabletop sections 31 and 32 may be variously constructed according to fancy and are identically formed and fitted together, and one section is secured substantially to the base 40 portions 23 and 25 of two of the slides, the other section being similarly secured to the base portions 24 and 26 of the remaining two slides. The top sections may include aprons 33 and 34 respectively or such frame structure as may be desired, as is 45 obvious. All the slides project beyond the sections to which they are connected toward the opposite sections, and the projecting portion of one slide is provided with two axles 35 and 36, the companion slide with similar axles 37 and 38, the slides assembled 50 on the companion guide bar likewise having axles 35', 36' and 37', 38', respectively, the axles being fixedly secured to the side bars of the slides and extending toward the guide bars. The axles of one slide have suitable 55 wheels or rollers 39 and 39' thereon respectively that are supported on the track portion 17 of one rail, the axles of the remaining slides having similar wheels or rollers 40 thereon that are supported on the 60 track portions of the adjacent rails.

A suitable number of filling boards 41 and 42 are provided as usual for effecting the extension of the table top, the boards being supported upon the slides when inserted in the required position to fill the gap 70 between the top sections when the latter are drawn apart.

The opposite ends of each guide bar have two horizontally arranged slots or recesses 43 and 43' respectively in which two grooved 75 pulleys or sheaves 44 and 45 are respectively mounted, and an endless chain or cable 46 is mounted on the two pulleys or sheaves, a similar chain 46' being mounted on two similar pulleys or sheaves 44' and 45' with 80 which the other of the two guide bars is provided. An axle 47 of each pulley or sheave preferably is driven upward from the bottom into the wood of the guide bar. The two companion slides are provided with 85 hook-bolts 48 and 49 having nuts 50 and 50' on their outer ends, the bolts extending through the side bars of the respective slides and having hooks 51 and 51' respectively that engage the chain 46 on opposite sides of 90 the guide bar 3, the other slides being similarly equipped with hook-bolts 48' and 49' connected with the chain 46'. Preferably one top section is provided with a latch 52 adapted to engage a stud 53 with which the 95 other top section is provided for holding the sections together. One end portion of each track rail is provided with a suitable stop 54 which may be suitably composed of a screw inserted through the base portion of 100 the track and into the wood of the guide bar, so as to be in the path of movement of the wheels on the track and prevent the wheels from being drawn away from the end of the track, the adjacent end of the slide having 105 a hole 55 therein through which the screw may be removed when desired.

In practical use, while moving each top section the base portions of its slides travel freely on the rollers 21, 21', to prevent the base 110 portions or the top sections from rubbing or having frictional resistance on the end portions of the guide bars, while the wheels or rollers of the slides roll in the track rails. As each top section is moved either toward or 115 from the companion section the chains or cables are caused to move on their guide pulleys or sheaves, so that both top sections must move together and consequently are always in balance. By this arrangement a 120 sectional or two-part pedestal is not required when a central support is desired.

Having thus described the invention, what is claimed as new is—

1. An extension table comprising a horizontal guide bar having a horizontal slot in each of the two opposite ends thereof, the bar having also a recess in each end thereof adjacent to the side of the bar, two guide rollers mounted in the recesses respectively, 125 130

two guide sheaves rotatably mounted in the slots respectively, an endless cable mounted on the sheaves, two track rails fixedly secured horizontally on the two opposite sides 5 respectively of the guide bar, two slides arranged on opposite sides respectively of the guide bar, each slide having a flat base portion and a depending side bar, the base portions of the slides being guided respectively 10 on the two rollers, each side bar having two wheels mounted thereon that are guided by the adjacent track rail, two devices securing the said side bars respectively to the cable on opposite sides respectively of the guide 15 bar, and two table tops fixedly secured to the base portions respectively of the slides.

2. An extension table comprising a horizontal guide bar having a slot in each of the two opposite ends thereof, the bar having 20 also a recess in each end thereof adjacent the side thereof, the two opposite sides of the bar having each a groove extending horizontally and from which the recesses extend, two guide rollers mounted in the recesses re-

spectively, two guide sheaves rotatably 25 mounted in the slots respectively, an endless cable mounted on the sheaves, two track rails fixedly secured in the two grooves respectively and having each a guard on its outer portion and also a guide on its upper portion, each guide having a guard thereon, two slides arranged on opposite sides respectively of the guide bar and guided respectively on the two rollers, each slide having two wheels mounted thereon that are guided 30 by the adjacent track rail adjacent the guide and guards thereof, two devices securing the two slides respectively to the cable on opposite sides respectively of the guide bar, and two table tops fixedly secured respectively to 35 the two slides.

In testimony whereof, I affix my signature in presence of two witnesses.

THOMAS M. MCKEE.
